United States Patent

Des. 236,550

Patented Aug. 26, 1975

236,550

CRYOGENIC FREEZER MODULE OR SIMILAR ARTICLE

Lyle L. Cann, Peotone, Ill., assignor to
Chemetron Corporation

Filed Feb. 9, 1973, Ser. No. 331,123

Term of patent 14 years

U.S. CL. D67—2 R   Int. CL. D15—07

FIG. 1

FIG. 2

FIG. 3

FIG. 4

FIG. 1 is a projected view of a cryogenic freezer module or similar article showing my new design;
 FIG. 2 is an end view thereof;

FIG. 3 is a top plan view thereof; and
 FIG. 4 is an elevational view thereof.

I claim:

The ornamental design for a cryogenic freezer module or similar article, as shown.
